UNITED STATES PATENT OFFICE.

ARTHUR P. HOLDEN AND PHILIP MORGAN, OF TORONTO, ONTARIO, CANADA.

BURNER FOR OIL-BURNING FURNACES.

Application filed September 23, 1926. Serial No. 137,357.

The principal objects of this invention are to ensure the maintenance of the nozzle and ignition points in the best condition to produce the highest efficiency in the burning of 5 the oil and to devise a structure which will enable the ready cleaning of the burner and the ignition points without disturbing adjustments.

A still further object is to devise a structure which is capable of being readily repaired without causing material interference with the use of the furnace.

The principal features of the invention consist in the novel construction and arrangement of parts whereby the burner nozzle is supported upon a hinged structure through which the supplies of oil and compressed air are directed separately to be united in the burner structure under conditions to ensure the preheating of the air and the thorough atomization of the oil discharged from the nozzle from a common discharge opening.

A further important feature consists in 25 adjustably supporting the ignition apparatus upon the hinged structure so that the adjustment thereof will be maintained during the manipulation of the hinged member for cleaning or inspection purposes.

In the drawings, Figure 1 is a front elevational view of the apparatus as applied to 30 a furnace door opening.

Figure 2 is a top plan view of the apparatus.

Figure 3 is a side elevational view showing the nozzle in the normal operating position.

Figure 4 is a side elevational view showing the nozzle swung outwardly on its 40 hinged support for inspection or repair purposes.

Figure 5 is a horizontal sectional detail through the line 5-5 of Figure 1 showing the oil and air distribution duct connection.

Figure 6 is a vertical mid-sectional view 45 through the nozzle.

In the burning of oil in domestic furnaces many difficulties arise through local conditions of atmosphere, draught, and the type 50 or condition of the furnace to which the burner is applied and it is frequently necessary to adjust or clean the nozzle or the ignition points for firing the oil vapour discharged from the nozzle.

55 It is important that the nozzle structure should be of such a nature as to enable such

cleaning or adjustments to be made in the simplest possible manner and in the least possible time and without disturbing adjustments and connections other than those actually required. 60

The present invention has been devised to enable these results to be accomplished and the exemplification of the invention as herein shown comprises a structure consisting of 65 a plate 1 which takes the place of a fire door and is secured to the fire door opening of the furnace. A bracket extension 2 extends downwardly from the plate 1 and is provided with a hub 3 having trunnion extensions 70 from each end and on each trunnion extension is arranged a hub 4 adapted to receive the end of a supply pipe.

L connections 5 are journalled on the outwardly extending end of the trunnion of 75 the hub, each being provided with suitable packing nuts 6 to form pressure tight joints.

Tubes 7 and 8 are secured in the upper connections of the L's 5 and curve inwardly at the upper end and enter a transverse hub 80 9 arranged upon a burner casting 10. The burner casting is provided with a flange 11 which is secured to a plate 12 which has a pair of downwardly extending arms 13 which rotatably encircle the trunnions on the ends 85 of the hub 3. It will thus be seen that the tubes 7 and 8, conducting air and oil to the burner, will swing upon the same centre as does the plate 12 supporting the burner casting. 90

The plate 12 is provided with a flange 14 which extends through an opening in the centre of the plate 1. This flange is provided with an elongated portion 15 at the bottom to protect the porcelain 16 of the ignition 95 points 17 against the intense heat which flows upwardly around the inner side of the fire box of the furnace.

The burner casting 10 which is hollow projects inwardly past the flange 14 and its 100 extension 15 and is provided at its inner end with a burner nozzle 18 which is of a suitable construction here shown having a whirling spiral member 19 arranged surrounding the oil feed pipe 20. The oil is fed directly to the point of the nozzle through the pipe 20 from a pipe 21 which extends into the packed recess 22 which connects with the tube 7. 105

The tube 8 connects with the chamber 110 within the hollow casting 10 and directs a flow of air thereinto, which is heated to

quite a high temperature by reason of its projecting into the combustion chamber of the furnace. The air thus heated also heats the oil and the two, raised to a high temperature, are projected from the nozzle in a fine spray. The edge of this spray is directed past the ignition points 17 and is ignited thereby and a jet of flame is projected angularly downward from the angularly disposed nozzle into the fire box of the furnace.

Suitable clean-out plugs 23 and 24 are arranged in the burner casting 10 to enable the interior of the casting to be thoroughly cleaned from grit of any kind.

Rigidly secured to the hinged plate 12 and extending outwardly at right angles therefrom are a pair of bars 25 and arranged between these bars and slidably supported thereon is a bracket member 26 to which a suitable electric transformer may be secured for providing the necessary high tension current for the ignition points.

The ignition points 17 are supported in the porcelains 16 and said porcelains are carried in the bracket 26. As previously mentioned, the bracket 26 is slidable on the bars 25 and is adjustably secured in any desired position of adjustment by the set screws 27 arranged in the sleeves 28 which encircle the bars 25.

A pivotal latch 29 is mounted between the lugs 30 arranged on the upper part of the plate 1. This latch engages the upper edge of the pivotal plate 12 and holds said plate in the closed position. When it is desired to inspect the nozzle or adjust it or clean it or the spark points, the latch is lifted and the plate 12 is swung outwardly upon the arms 13 as illustrated in Figure 4, thus bringing the nozzle and the ignition points out clear of the enclosing structure.

The pivoting of the feed pipe eliminates the necessity of disconnecting any pipe connections and enables inspection and cleaning of the nozzle without altering any adjustments whatever.

The entire structure is extremely compact and neat in appearance. It is sturdy in its construction and there is nothing that will readily get out of order.

What we claim as our invention is:

1. A burner for oil burning furnaces, comprising a plate adapted to be rigidly secured to the furnace structure and having an opening therethrough and a downwardly extending rigid bracket, trunnions horizontally arranged extending from said rigid bracket and having rigid hollow extensions, supply pipes connected with said hollow extensions, hollow L-fittings rotatably mounted on said trunnion extensions, tubes extending upwardly from said L-fittings, a plate having arms pivotally mounted on said trunnions, a burner nozzle rigidly se-

cured to said pivotal plate and extending through the opening in the rigid plate into the interior of the furnace, said tubes being connected to said burner nozzle, and a pair of high tension ignition points adjustably mounted on said pivotal plate and extending therethrough into the interior of the furnace.

2. A burner for oil burning furnaces, comprising a plate adapted to be rigidly secured to the furnace structure and having an opening therethrough and a downwardly extending rigid bracket, trunnions horizontally arranged extending from said rigid bracket and having rigid hollow extensions, supply pipes connected to said hollow extensions, hollow L-fittings rotatably mounted on said trunnion extensions, tubes extending upwardly from said L-fittings, a plate having arms pivotally mounted on said trunnions, a burner nozzle rigidly secured to said pivotal plate and extending through the opening in the rigid plate into the interior of the furnace, said tubes being connected to said burner nozzle, a bracket slidably mounted on said pivotal plate and adapted to support an electric transformer, ignition terminals carried by and insulated from said bracket and extending through the pivotal plate into the interior of the furnace, and a flange arranged on said pivotal plate extending inwardly and protecting the insulation of said ignition terminals.

3. In an oil burner for furnaces, the combination with a furnace having a fire door opening, of a metal plate adapted to be rigidly secured to the furnace structure to close said opening and having an opening therethrough, a hub rigid with said rigid plate and spaced directly below the opening therein, a pair of hollow pivot extensions on said hub in axial alignment and having their interiors unconnected, a plate pivotally mounted on said hollow pivot extensions, a burner nozzle carried by said pivotal plate, ignition means carried by said pivotal plate, said nozzle and ignition means being adapted to extend through the opening in said rigid plate into the furnace interior, an air supply pipe leading to and conducting air under pressure to the interior of one of said hollow pivot extensions, an oil supply pipe leading to and conducting oil to the other of said hollow extensions, and tubular connections connecting each of said hollow pivot extensions with said burner nozzle.

4. In an oil burner for furnaces, the combination with a furnace having a fire door opening, of a metal plate adapted to be rigidly secured to the furnace structure to close said opening and having an opening therethrough, rigid bracket extensions from said rigid plate having a hub cast integral with their outer ends, hollow pivot extensions extending axially from opposite ends

of said hub, said hollow pivot extensions being each closed at their inner end, a plate having lug extensions encircling said hollow pivot extensions adjacent the hub, an oil nozzle mounted on said pivotal plate, ignition terminals mounted on said pivotal plate directly below said nozzle, said nozzle and ignition terminals being adapted to extend through the opening in said rigid plate into the furnace interior, separate oil and air supply pipes leading to said hollow pivot extensions and conducting oil to one of said hollow pivot extensions and air to the other, means for separately conducting oil and air to said burner nozzle through the opening in said rigid plate, and oil and air conducting means connecting the interiors of said hollow pivot extensions with said conducting means.

20 5. In an oil burner for furnaces, the combination with the fire door opening, of a

plate rigidly secured thereover and closing said opening and having an opening therethrough, a bracket member extending rigidly from said plate, a member hinged to said rigid bracket member, a hollow burner casing secured to said hinged member and extending through the opening in said plate into the furnace interior, a pipe connection leading to the interior of said hollow burner casing for conducting air thereto under pressure, a discharge outlet at the inner end of said burner casing, an oil nozzle directing oil through said outlet, a pipe connection leading to the oil nozzle and separate means pivotally connected with said air and oil nozzle connections for conducting air under pressure and oil to the same independent of the swinging of said hinged member.

ARTHUR P. HOLDEN.
PHILIP MORGAN.
